SPECIAL WORK SEWING MACHINE.
APPLICATION FILED MAR. 13, 1915.

Patented Apr. 24, 1917.

UNITED STATES PATENT OFFICE.

ARTHUR ROSENTHAL, OF GRAND RAPIDS, MICHIGAN, ASSIGNOR TO ROSE LABEL MACHINE COMPANY, OF GRAND RAPIDS, MICHIGAN.

SPECIAL-WORK SEWING-MACHINE.

1,223,617.

Specification of Letters Patent. Patented Apr. 24, 1917.

Application filed March 13, 1915. Serial No. 14,236.

To all whom it may concern:

Be it known that I, ARTHUR ROSENTHAL, a citizen of the United States, residing at Grand Rapids, county of Kent, State of Michigan, have invented certain new and useful Improvements in Special-Work Sewing-Machines, of which the following is a specification.

This invention relates to improvements in special work sewing machines and relates particularly to improvements in sewing machines for stitching labels or similar pieces of material to a garment or other piece of work. This invention consists in improvements upon the special work sewing machine disclosed in the pending application of Arthur Rosenthal and Michael Petrocchi Serial No. 797,661, filed October 27, 1913.

The objects of this invention are:

20 First, to provide, in a machine of the class described, improved label feeding mechanism and improved means for actuating the same.

Second, to provide, in a machine of the class described, improved means for actuating the upper thread cutting knife.

Third, to provide, in a machine of the class described, an improved work holder and label holder of simplified construction and to 30 provide improved means for actuating the same.

Further objects, and objects relating to details and economies of construction and operation will definitely appear from the 35 detailed description to follow.

I accomplish the objects of my invention by the devices and means described in the following specification. The invention is clearly defined and pointed out in the claims. 40 A structure constituting a preferred embodiment of my invention is illustrated in the accompanying drawings forming a part of this specification, in which:

Figure I is a fragmentary view in side 45 elevation of a portion of a sewing machine embodying my invention.

Fig. II is a rear perspective view of the head portion of a sewing machine showing my invention embodied therein.

50 Fig. III is a view in front elevation of the work holder and label holder members and the label feeding mechanism.

Fig. IV is a sectional plan view, taken on a line corresponding to line 4—4 of Figs. I,

III and V, the work holder being shown in 55 its position at the end of the cycle.

Fig. V is a longitudinal sectional view taken on a line corresponding to the line 5—5 of Figs. III and IV, and showing in detail, the work holder, label holder and label feeding mechanism, and the arrangement 60 of the upper thread cutting knife and the means for actuating the same.

Fig. VI is a detail, perspective view of the work holder presser foot detached from the 65 machine.

Fig. VII is a fragmentary, detail, perspective view showing a portion of the work holder carrying arm and the presser foot 70 guide head carried thereby.

Fig. VIII is a detail, perspective view of the label holder presser foot guide head detached from the machine.

Fig. IX is a detail, perspective view of the label holder presser foot detached from the 75 machine and enlarged.

Fig. X is a detail, perspective view of the label follower and the actuating mechanism therefor.

Fig. XI is a detail, perspective view of the 80 label follower.

Fig. XII is a detail, perspective view of the label guide plate.

Fig. XIII is a detail, perspective view of the bottom plate of the work holder presser 85 foot.

Fig. XIV is a detail, perspective view of the bell crank lever for retracting and projecting the upper thread cutting knife.

Fig. XV is a detail, perspective view of 90 the upper thread cutting knife.

Fig. XVI is a detail, perspective view of the spring for the upper thread cutting knife.

Fig. XVII is a detail, perspective view of 95 the cam member carried by the sewing machine head for actuating the label feeding mechanism.

In the drawing, similar reference characters refer to similar parts throughout the 100 several views, and the sectional views are taken looking in the direction of the little arrows at the ends of the section lines.

Considering the numbered parts of the drawings, the machine comprises the base 1, 105 the guide base 2 and the head 3 on the arm 4. On the arm 4 the elevating lever 5 is mounted on the rock shaft 6 which carries

the arm 7 for releasing the tension device 8. The link 10 is pivoted at 11 to the end of the elevating lever 5. The work holder guide head 19, which is suitably guided on the base of the machine, is provided with a series of internal racks 20 with which the driving gear 21 meshes, so as to drive said work holder guide head in a predetermined path. The work holder guide head carries 10 the arm 22 to the forward end of which the presser foot guide head 23 is secured. These parts form no part of my present invention and hence will not be described in detail here, the same being of known construction, such as is shown in the patent application of Michael Petrocchi, Serial No. 736,257, filed December 12, 1912, the patent application of Arthur Rosenthal, Serial No. 736,258, filed December 12, 1912, and the 15 patent application of Arthur Rosenthal and Michael Petrocchi, Serial No. 797,661, filed October 27, 1913.

The presser foot guide head 23 is provided at the sides with the flanges 21 and 25 is also provided with the ways 25 and the way 26. A plate 27 is secured to the rear face of said guide head, partially covering said way 26, and provided with a notch 27' in its upper edge for a purpose presently 30 to be described. The cloth guard 28 is secured to the lower edge of the arm 22 and provided with a downturned flange 28' to which the upturned flange 29' of the bottom work plate 29 of the work holder is secured.

The label holder presser foot guide head 30 is provided with flanges 31 disposed in the ways 25 of the presser foot guide head 23 so that said label holder presser foot 40 guide head 30 is slidably mounted on said presser foot guide head. A notch 32 is provided in the lower part of said label presser foot guide head 30 to accommodate the projections 47' carrying the bell crank lever 47 for actuating the upper thread cutting knife. The label holder presser foot 33 is secured to the forward face of the guide head 30 by the screws 34. A frame-like label holder member 35 is secured to the presser 45 foot 33 by the screws 36, said frame-like member 35 having portions 37 on their lower edges to grip the edges of the label. The work holder presser foot 38, having the legs 38', is provided with ways 39 in which the flanges 24 of the presser foot guide head 23 are disposed so that said work holder presser foot 38 is slidably mounted on said presser foot guide head 23. A notch 40 is formed in the upper edge of said work holder presser 50 foot and there is a space 41 between the legs 38' of said presser foot 38. The legs 38' are provided with forwardly projecting arms 42 extending on either side of guide head 23, to which the side members 43 of the label feed slide are secured by the screws 44.

A slide 45 is disposed in the way 26, the upper end of said slide being provided with an upwardly extending arm 46 on the upper end of which is journaled a roller 43 which is adapted to be brought in line with the hook 42 secured to the lower end of the link 10 carried by the end of the elevating lever 5. A block 45 is secured to the rear face of the sewing machine head, as shown in Fig. 11, and said block carries an L-shaped member 46, the upright portion of which is provided with a slot 47. A pin 48 fixed on the end of link 10 is disposed in said slot so as to guide the same and insure its reciprocation in a vertical plane. The bell crank lever 47 is journaled on the pivot pin 48 through projections 47' (Fig. VIII) disposed at the back of and carried by the guide head 30 and disposed in the opening 32, said bell crank lever having an arm 49 which is disposed in an elongated opening 46 provided in the slide 45. Bell crank lever 47 is provided with a shoulder 50 which engages the top of the label holder presser foot 33 to limit the rocking movement of said bell crank, and said bell crank lever has its lower arm provided with a projecting finger 51 which is disposed in a notch 53 formed in the upper thread cutting knife 52 which is slidably mounted in the lower portion of the label holder presser foot 33. Knife 52 is provided with a notch 54' through which the needle may reciprocate, one edge of said notch being formed with a cutting edge 54. The knife is also provided with an upwardly-projecting beveled portion 55 to deflect the needle into the opening 54' or outside and prevent the point of needle from engaging the knife. This is a safety device and is of consequence only when there is a slight over feed. The knife is held in place by the frictional contact of the flat spring 56 engaging over the top surface thereof, as shown in Fig. V.

Brackets having laterally projecting arms 57 are secured to the front face of the guide head 23 by the screws 58. A bar 59 is secured by the screws 60 to the guide head 30 and pins 61 are disposed in aligned openings provided in the ends of said arms 57 and in the ends of the bar 59. The lower ends of said pins are threaded and nuts 62 are adjustable thereon. The pins 61 have heads 63 and compression springs 64 are disposed on the pins 61 between the heads 63 and the bar 59, tending to force the bar 59 and the guide head 30, by which it is carried, downward. Stop pins 65 are secured to the work holder presser foot 38, as shown in Figs. V and VI, against which the bar 59 strikes as it moves upward so that the work holder presser foot and the label holder presser foot will be lifted a certain distance from the work holder presser foot.

A pin 66 is slidably mounted at its for-

- ward end in the plate 67 carried by the guide head 23, and at its rear end in the flanges 28' and 29' of the cloth guard 28 and the bottom work plate, as shown in Fig. V. A 5 collar 68 is fixed on said pin in front of the upturned flange 29' and a compression spring 69 is disposed on said pin 66 between the plate 67 and the collar 68. The rear end of the pin 66 projects rearwardly, as shown 10 in Fig. V, in position to be engaged by a wear plate 70 on the guide casing 2 when the arm 22 and the parts carried thereby are moved rearwardly during the cycle of the machine.
- 15 Groove 79 is provided in one of the side members 43 of the label slide, and a bar 78 is reciprocably mounted in said groove 79, said bar carrying at its forward end the label follower 80 which is attached at one 20 edge to the bar 78 and extends across the label slide. The bar 78 is reciprocated by the mechanism which I will now describe. An arm 71 is mounted on the work holder presser foot 38, said arm having a slot 72 in 25 its outer end in which the upper end of lever 73 is fulcrumed on the pivot 74. The lower end of lever 73 is offset somewhat at 75 and provided with a notch 76 in which a pin 77 carried by the rear end of the bar 78 is disposed. A latch 81 is pivoted at 82 to the 30 lever 73, the upper end of said latch being provided with the notch 83 in the edge thereof which engages a locking pin 84 fixed on the side of the arm 71. The 35 upper end of the latch 81 is beveled as at 85. A spring 86 is connected to the latch 81 at 87, a slight distance above the pivot 82, the other end of said spring 86 being fixed to the pin 88 carried by the presser 40 foot 38. A bracket 90 is secured to the sewing machine head 3 by the screws 91, said bracket being provided with a downwardly extending arm 92 having a cam edge and a rearwardly and downwardly extending portion 93, the latter being adapted to engage the beveled end 85 of the latch 81 when the work holder presser foot and the parts carried thereby are raised, so as to trip the latch 81 so that the spring 86 will actuate 45 lever 73 to reciprocate the label follower. A laterally projecting arm 89 is formed on the lever 73 and during the cycle of the machine, the movement of the work carrying arm and the parts carried thereby will 50 bring said arm 89 in line with the arm 92 of the bracket 90 so as to rock the lever 73 on its pivot to retract the label follower. The label follower is automatically latched in retracted position by latch 81.
- 55 Arms 94 project from the rear edge of the label follower 80, having an opening 95 therebetween and the forward ends of said arms are provided with downwardly and rearwardly projecting fingers 96. A label 60 guide plate 97 is secured to the side mem- bers 43 of the label slide, said guide plate being provided with rearwardly and downwardly projecting fingers 98 and 99, the central finger 98 being narrower than the outer fingers 99 so that it is disposed in opening 70 65 when the follower is in its forward position. The bottom plate 100 is secured to the bottom surfaces of the side members 43 and is provided with a pair of slots 101 in which the lower edges of fingers 96 are disposed to guide the label follower, as it is actuated by the reciprocating bar 78. The top plate 102 is secured to the upper surfaces of the side members 43 by screws 103, said top plate being provided with an opening 104 75 through which the label is inserted in place relative to the label follower. The bottom plate 105 is secured to the bottom of the work holder presser foot and is provided with a label opening 106 corresponding in size to the label and with upright posts 107 projecting adjacent the rear edge of said opening 106 and acting as a stop for the rear edge of the label as it is fed into place over said opening 106.
- 80 From the description of the parts given above, the operation of the machine should be very readily understood. Figs. IV and V show the parts in the position which they occupy at the end of the cycle of the machine. As the parts are shown in said views, the elevating lever 5 has lifted the hook 12 sufficiently to lift the slide 45 a short distance, acting on the arm 49 of the bell crank 47 to rock the same and retract the upper thread cutting knife 52 to cut the upper thread. The further lifting of the hook 12 and the slide 45 lifts the guide head 30, by which the label holder presser foot is carried, inasmuch as the 85 shoulder 50 of the bell crank lever 47 is in engagement with the top of the label holder presser foot 33, as shown in Fig. V. This causes the label holder presser foot to be lifted slightly above the bottom plate of 90 the work holder presser foot, or until the bar 59 strikes the stop pins 65 on the work holder presser foot. The further upward movement of the slide 45, due to the elevating lever 5, lifts the work holder presser 95 foot and the label holder presser foot so that they are lifted above the work plate 29 to permit the removal of the work. As the work holder presser foot is lifted, the upper end 85 of the latch 81 engages the downwardly extending portion 93 of the bracket 90 which is fixed to the sewing machine head, the upper end of the latch 81 having been brought in line with said cam portion 93 by the movement of guide head 100 120 23 during the cycle of the machine. The engagement of latch 81 with the portion 93 of bracket 90 causes the notch 83 to be disengaged from pin 84 allowing the spring 86 to rock the arm 73 on its pivot 74 so as 125 130

4. to reciprocate the slide 78. The label has previously been inserted through the opening 104 in the rear of the label follower fingers 96 and as the slide 78 is reciprocated, the label is above the bottom plate 106 of the work holder presser foot with its rear edge abutting the stops 107 and beneath the label holder member 35 in position to be engaged by the gripping edges 37 thereof when the label holder presser foot is depressed. A fresh piece of work is inserted upon the work holder plate 29 and the elevating lever is manipulated so as to allow the springs 61 to force the work holder presser foot and the label holder presser foot downwardly. The work holder presser foot descends upon the work, holding it in place upon the movable work plate 29, and the label holder presser foot 35 descends and by its edges 37 holds the label in place upon the work. The gear 21 now drives the work holder guide head in a predetermined path as will be seen by a reference to Fig. IV, first moving downwardly, then to the left of Fig. IV, then upwardly, then to the right of Fig. IV and then downwardly to the initial position, in which the parts are shown in Fig. IV.

As the work holder guide head moves rearwardly or to the left of Fig. IV, the rear end of the pin 66 engages the wear plate 70 on the stationary guide base 2 and the pin 66 is forced forwardly so that its forward end engages the rock lever 47 and rocks the same on its pivot to project the upper thread cutting knife 52 so that the notch 54 thereof is in line with the stitching along the rear edge of the label. The elongated opening 46 is provided in slide 45 so as to permit of the movement of bell crank 47 independently of slide 45. As the work is moved around in a predetermined path by the work holder carrying head and arm, it is brought to a final position in which the needle reciprocates through the notch 54 in the thread cutting knife. At the end of the cycle of the machine, by mechanism which is not shown or described here, but which is shown in the prior applications above referred to, the stitching mechanism is stopped with the needle in elevated position so that when the knife 52 is retracted, it will cut the upper thread.

As the work holder carrying arm moves from its initial position upwardly, in Fig. IV of the drawing, the laterally projecting arm 89 on lever 73 will be brought in line with the downwardly projecting arm 92 of the bracket 90. Then, as the work holder carrying arm moves toward the left of Fig. IV, the arm 92 will engage the projecting arm 89 so as to rock the lever 73 on its pivot carrying the bar 78 and the label follower 80 to its outer position. The notch 83 in the latch 81 engages the pin 84 and

the spring 86 holds said notch in engagement with the pin so that the label follower is held in its outer position and is, so to speak, cocked ready to be tripped when the work holder presser foot is lifted at the completion of the cycle of the machine. After the label follower has been cocked in this manner, it is in position to receive a fresh label which is fed through the opening 104 by the operator so that when at the completion of the stitching movement, the work holder presser foot is lifted, a new label will be fed into place beneath the label holder member, as has already been described.

80 The label feeding mechanism shown in this application is especially designed for use in connection with labels which are somewhat stiff such as labels which have been starched and which will lie flat beneath the label holder member after they have been fed into place by the label follower. In view of this fact, I have been able to design a label feeding mechanism consisting of but few parts and consisting broadly in 85 automatic means for feeding the labels into place, and a label holder member which descends and grips the edges of the label to hold it while it is being stitched.

90 I am aware that the particular structure 95 which I have here shown is susceptible of considerable variation without departing from the spirit of my invention and, therefore, I do not wish to be restricted to the same. I have found, however, that this 100 form is to be preferred and, therefore, I desire to claim the same specifically as well as broadly as indicated by the appended claims.

Having thus described my invention, what 105 I claim as new and desire to secure by Letters Patent, is:

1. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said 110 work holder presser foot and said label holder presser foot relative to the base of the machine, an automatic thread cutting means, a label slide comprising side members carried by said work holder presser foot, a bottom plate secured to said side members and provided with slots, a slideable bar mounted on said slide, a label follower secured at one end to said slide bar, fingers carried by said follower and disposed in the 115 slots of said bottom plate, a spring lever carried by the work holder presser foot and connected at its lower end to the rear end of said slide bar, a notched latch pivoted on said lever, a locking pin to engage said 120

latch, a trip means for said latch secured to the head of the machine adapted to engage the upper end of said latch and trip the same when the work holder presser foot is lifted, 5 and a downwardly projecting arm on the head of the machine disposed and adapted during the movement of the work carrying arm to engage said laterally projecting arm on said lever to rock the same on its pivot 10 and thereby automatically latch said follower in its outer position, all coacting substantially as described and for the purpose specified.

2. In a machine of the class described, the combination with the base, arm and head of a sewing machine, of a work carrying arm, means for moving said work carrying arm in a predetermined path, a work holder presser foot and a label holder presser foot 15

carried by said arm, means for lifting said label holder presser foot relative to said work holder presser foot and said label holder presser foot relative to the base of the machine, a label slide comprising side

members carried by said work holder presser foot, a bottom plate secured to said side members and provided with slots, a slidable bar mounted on said slide, a label follower secured at one end to said slidable bar, fingers

carried by said follower and disposed in the slots of said bottom plate, a spring lever carried by the work holder presser foot and connected at its lower end to the rear end of said slidable bar, a notched latch pivoted on said lever, a locking pin to engage said latch, trip means for said latch secured to the head of the machine adapted to engage the upper end of said latch and trip the same when the work holder presser foot

is lifted, and a downwardly projecting arm on the head of the machine disposed and adapted during the movement of the work carrying arm to engage said laterally projecting arm on said lever to rock the same

on its pivot and thereby automatically latch said follower in its outer position, all coacting substantially as described and for the purpose specified.

3. In a machine of the class described, the combination with the base, arm and head of a sewing machine, of a work carrying arm, means for moving said work carrying arm in a predetermined path, a work holder presser foot and a label holder presser foot

carried by said arm, means for lifting said label holder presser foot relative to said work holder presser foot and said label holder presser foot relative to the base of the machine, a label slide comprising a bottom plate provided with slots, a slidable bar mounted on said slide, a label follower secured at one end to said slidable bar, fingers

carried by said follower and disposed in the slots of said bottom plate, a spring lever carried by the work holder presser foot and connected at its lower end to the rear end of said slidable bar, a notched latch pivoted on said lever, a locking pin to engage said latch, and a trip means for said latch secured to the head of the machine adapted to engage the upper end of said latch and trip the same when the work holder presser foot

is lifted, and a downwardly projecting arm on the head of the machine disposed and adapted during the movement of the work carrying arm to engage said laterally projecting arm on said lever to rock the same

on its pivot and thereby automatically latch said follower in its outer position, all coacting substantially as described and for the purpose specified.

4. In a machine of the class described, the combination with the base, arm and head of a sewing machine, of a work carrying arm, means for moving said work carrying arm in a predetermined path, a work holder presser foot and a label holder presser foot

carried by said arm, means for lifting said label holder presser foot relative to said work holder presser foot and said label holder presser foot relative to the base of the machine, a label slide comprising a bottom plate provided with slots, a slidable bar mounted on said slide, a label follower secured at one end to said slidable bar, fingers

carried by said follower and disposed in the slots of said bottom plate, a spring lever carried by the work holder presser foot and connected at its lower end to the rear end of said slidable bar, a notched latch pivoted on said lever, a locking pin to engage said latch, and a trip means for said latch secured to the head of the machine adapted to engage the upper end of said latch and trip the same when the work holder presser foot

is lifted, and a downwardly projecting arm on the head of the machine disposed and adapted during the movement of the work carrying arm to engage said laterally projecting arm on said lever to rock the same

on its pivot and thereby automatically latch said follower in its outer position, all coacting substantially as described and for the purpose specified.

5. In a machine of the class described, the combination with the base, arm and head of a sewing machine, of a work carrying arm, means for moving said work carrying arm in a predetermined path, a work holder presser foot and a label holder presser foot

carried by said arm, means for lifting said label holder presser foot relative to said work holder presser foot and said label holder presser foot relative to the base of the machine, a label slide comprising a bottom plate provided with slots, a slidable bar mounted on said slide, a label follower secured at one end to said slidable bar, fingers

carried by said follower and disposed in the slots of said bottom plate, a spring lever carried by the work holder presser foot and connected at its lower end to the rear end of said slidable bar, a notched latch pivoted on said lever, a locking pin to engage said latch, and a trip means for said latch, coacting substantially as described and for the purpose specified.

6. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and said label holder presser foot relative to the base of the machine, a label slide, a follower adapted to coöperate therewith to deliver the label beneath the label holder presser foot, means for actuating said follower comprising a spring lever, a notched latch pivoted on said lever, a locking pin to engage said latch, and a trip means for said latch, coacting substantially as described and for the purpose specified.
7. In a machine of the class described, the combination of a work holder presser foot and a label holder presser foot coöperating therewith, means for lifting said label holder presser foot relative to said work holder presser foot and said work holder presser foot relative to the base of the machine, a label feeding means comprising a label slide carried by said work holder presser foot, a label follower coöperating with said slide, spring means for urging said follower forward to deliver the label to place, automatic means for retracting the same to permit a label to be placed in front of the same, and a release means to permit the label follower to act on the elevation of the label holder to feed the label beneath the label presser foot when it is elevated, as specified.
8. In a machine of the class described, the combination of a work holder presser foot, a label holder presser foot for holding a label on the work, means for elevating the label holder presser foot in relation to the work holder presser foot, and a label feeding means comprising a label slide carried by the work holder presser foot, a label follower arranged to engage the rear edge of a label in said slide, and means for retracting the follower whereby the label can be placed manually in front of said follower and be delivered by the follower into position beneath the label presser foot, as specified.
9. In a machine of the class described, the combination of a work holder presser foot, a label holder presser foot for holding a label on the work, means for elevating the label holder presser foot in relation to the work holder presser foot, and a label feeding means comprising a label slide carried by the work holder presser foot, and a label follower arranged to engage the rear edge of a label in said slide, as specified.
10. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and for lifting said work holder presser foot and said label holder presser foot relative to the base of the machine, a label feed slide, a label follower arranged to engage the edge of a label, and means for actuating said follower at predetermined intervals during the cycle of the machine, all coacting substantially as described.
11. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and for lifting said work holder presser foot and said label holder presser foot relative to the base of the machine, a label slide, a label follower slidable thereon, a lever pivoted on said work holder presser foot and connected to said label follower to reciprocate the same, spring means for rocking said lever to bring the follower to its inner position to feed a label, latch means for holding said lever with said label follower in its outer position, means engageable when the work holder presser foot is lifted for tripping said latch means whereby said spring means brings said label follower to the inner position, and means engageable during the movement of the work carrying arm, for rocking said lever to carry the follower to its outer position, all coacting substantially as described.
12. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and for lifting said work holder presser foot and said label holder presser foot relative to the base of the machine, and a label feeding means comprising a label follower, spring means normally urging said label follower to its inner position to feed a label, means for holding said follower in its outer position against the tension of said spring means, released by the upper movement of said work holder presser foot, and means actuated by the movement of said work carrying arm for moving said follower to its outer position.

13. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and for lifting said work holder presser foot and said label holder presser foot relative to the base of the machine, and a label feeding means comprising a label follower, spring means normally urging said label follower to its inner position to feed a label, means for holding said follower in its outer position against the tension of said spring means, and means actuated by the movement of said work carrying arm for moving said follower to its outer position.
14. In a machine of the class described, the combination with the base, arm and head of a sewing machine, of a work carrying arm, means for moving said work carrying arm in a predetermined path, a work holder presser foot and a label holder presser foot carried by said arm, means for lifting said label holder presser foot relative to said work holder presser foot and for lifting said work holder presser foot and said label holder presser foot relative to the base of the machine, said work holder presser foot being provided with forwardly projecting arms extending on each side of said label holder presser foot, a label slide comprising side members secured to said forwardly projecting arms, an actuating bar, a label follower secured to said bar, and means for actuating said actuating bar at predetermined intervals during the cycle of the machine, all coacting substantially as described.
15. In a machine of the class described, the combination with the base, arm and head of a sewing machine, of a work carrying arm, means for moving said arm in a predetermined path, a guide head secured to said work carrying arm, a work holder presser foot slidably mounted on said guide head, a label holder presser foot slidably mounted on said guide head, a bell crank lever pivoted in said label holder presser foot, an upper thread cutting knife slidably mounted in said label holder presser foot and provided with a notch in its rear end, a finger on said bell crank lever disposed in said notch, a slide member carried by said guide head and provided with an elongated slot, said bell crank having an arm disposed in said slot, means for lifting said slide member to rock said bell crank to actuate said knife in one direction, a slidably mounted pin carried by said work carrying arm and having its forward end disposed in proximity to said bell crank, a spring normally urging said pin away from said bell crank, a stationary part with which the rear end of said pin is adapted to contact as said work carrying arm moves rearwardly during the cycle of the machine whereby said pin is forced forwardly to rock said bell crank and to actuate said knife in the other direction, all coacting substantially as described.
16. In a machine of the class described, the combination with the base, arm and head of a sewing machine, of a work carrying arm, means for moving said arm in a predetermined path, a guide head secured to said work carrying arm, a work holder presser foot slidably mounted on said guide head, a label holder presser foot slidably mounted on said guide head, a bell crank lever pivoted in said label holder presser foot, an upper thread cutting knife slidably mounted in said label holder presser foot, connections between said bell crank lever and said knife, a slide member carried by said guide head and provided with an elongated slot, said bell crank having an arm disposed in said slot, means for lifting said slide member to rock said bell crank to actuate said knife in one direction, a slidably mounted pin carried by said work carrying arm and having its forward end disposed in proximity to said bell crank, a spring normally urging said pin away from said bell crank, a stationary part with which the rear end of said pin is adapted to contact as said work carrying arm moves rearwardly during the cycle of the machine whereby said pin is forced forwardly to rock said bell crank and to actuate said knife in the other direction, all coacting substantially as described.
17. In a machine of the class described, the combination with the base, arm and head of a sewing machine, of a work carrying arm, means for moving said arm in a predetermined path, a guide head secured to said work carrying arm, a work holder presser foot slidably mounted on said guide head, a label holder presser foot slidably mounted on said guide head, a bell crank lever pivoted in said label holder presser foot, an upper thread cutting knife slidably mounted in said label holder presser foot, connections between said bell crank lever and said knife, a slide member carried by said guide head and provided with an elongated slot, said bell crank having an arm disposed in said slot, means for lifting said slide member to rock said bell crank to actuate said knife in one direction, a slidably mounted pin carried by said work carrying arm and having its forward end disposed in proximity to said bell crank, a stationary part with which the rear end of said pin is adapted to contact as said work carrying arm moves rearwardly during the cycle of the machine whereby said pin is forced forwardly to rock said bell crank and to actuate said knife in the other direction, all coacting substantially as described.

said knife in the other direction, all coacting substantially as described.

18. In a machine of the class described, the combination of a base, arm and head of a sewing machine, of a work carrying arm, means for moving said arm in a predetermined path, a work holder presser foot, a label holder presser foot, means for lifting said work holder presser foot and said label holder presser foot, an upper thread cutting knife slidably mounted in said label holder presser foot, means for actuating said knife in one direction, actuated by said lifting means, and means for actuating the knife in the other direction actuated by the movement of said work carrying arm.

19. In a machine of the class described, the combination with the base, arm and head of a sewing machine, of a work carrying arm, means for moving said arm in a predetermined path, a guide head secured to the end of said arm, a work holder presser foot slidably mounted on said guide head and provided with forwardly projecting arms, a label holder presser foot guide head slidably mounted on said main guide head, a label holder presser foot secured thereto and adapted to grip the edges of the label when said label holder presser foot descends, an upper thread cutting knife slidably mounted in said label holder presser foot, a bell crank journaled in said label holder presser foot guide head and connected to said knife, a slide member mounted in said guide head between said guide head and said work holder presser foot and actuating said bell crank, means for lifting said slide member, stop means for limiting the upward movement of said label holder presser foot relative to said work holder presser foot, and means actuated by the movement of said work carrying arm for rocking said bell crank in one direction, all coacting substantially as described and for the purpose specified.

20. In a machine of the class described, the combination with the base, arm and head of a sewing machine, of a work carrying arm, means for moving said arm in a predetermined path, a guide head secured to the end of said arm, a work holder presser foot slidably mounted on said guide head and provided with forwardly projecting arms, a label holder presser foot guide head slidably mounted on said main guide head, a label holder presser foot secured thereto

and adapted to grip the edges of the label when said label holder presser foot descends, an upper thread cutting knife slidably mounted in said label holder presser foot guide head and connected to said knife, a slide member mounted in said guide head between said guide head and said work holder presser foot and actuating said bell crank, means for lifting said slide member, stop means for limiting the upward movement of said label holder presser foot relative to said work holder presser foot, all coacting substantially as described and for the purpose specified.

21. In a machine of the class described, the combination with the base, arm and head of a sewing machine, of a work carrying arm, means for moving the same in a predetermined path, a work holder presser foot, a label holder presser foot, a slide for lifting said work holder presser foot and said label holder presser foot, a roller journaled in the upper end of said slide, an elevating lever pivoted to the arm of said sewing machine, a link pivoted to the end of said lever and provided with a hook adapted to engage said roller in one position of the work carrying arm, a guide member secured to the head of the sewing machine and provided with a slot, a pin carried by the end of said link and disposed in said slot so as to insure the movement of said hook in a vertical plane, and means for actuating said elevating lever.

22. In a machine of the class described, the combination with the base, arm and head of a sewing machine, of a work carrying arm, means for moving the same in a predetermined path, a work holder presser foot, a label holder presser foot, a slide for lifting said work holder presser foot and said label holder presser foot, a roller journaled on the upper end of said slide, an elevating lever pivoted to the arm of said sewing machine, a link pivoted to the end of said lever and provided with a hook adapted to engage said roller in one position of the work carrying arm, and means for actuating said elevating lever.

. In witness whereof, I have hereunto set my hand and seal in the presence of two witnesses.

ARTHUR ROSENTHAL. [L.S.]
